CLAIM

The ornamental design for an exercise band handle, as shown and described.

DESCRIPTION

FIG. 1 is an isometric view of the exercise band handle, showing the new design.

FIG. 2 is an isometric sectional view thereof.

FIG. 3 is a front view thereof.

FIG. 4 is a back view thereof.

FIG. 5 is a top view thereof.

FIG. 6 is a bottom view thereof.

FIG. 7 is a left side view thereof; and,

FIG. 8 is a right side view thereof.

The cross-hatched portions of the drawings are for illustrative purposes only and form no part of the claimed design.

1 Claim, 4 Drawing Sheets(56)
